12 Claims. (Cl. 179—171)

Amplifier tubes having an electron multiplying action are known as electron multiplier tubes. In these tubes the primary electrons emitted by a cathode are controlled by a control grid and accelerated by a screen grid, whereupon they impinge on a multiplying electrode and there give rise to a secondary emission, the relatively large number of secondary electrons thus released passing to the working anode.

The present invention relates to the use of tubes of this kind in amplifier circuits, but it is not concerned with the construction of the tubes themselves or of the multiplying electrodes which they contain. Thus the tubes hereinafter referred to have only one multiplying electrode but it will be obvious that the invention can equally well be applied in the case of tubes with a plurality of such electrodes.

It is characteristic of the working of these tubes that their anode current is derived from two sources; (1) from the primary thermal emission of the incandescent cathode and (2) from the secondary emission of the multiplying electrode. If we define as "positive" current the direction of the anode current of an ordinary electron tube (that is to say, the direction opposite to that in which the electrons travel) we shall have, in a multiplier tube, two electrodes with a "negative" current, i. e. the incandescent cathode and the positively charged multiplying electrode.

It is the object of the present invention to provide circuit conditions which make allowance for the aforementioned unusual conditions under which the anode current is derived and to enable stable and efficient working to be obtained. The voltage current characteristic of a multiplying electrode is the well known dynatron characteristic shown in Fig. 1 of the attached drawings.

To ensure a stable working point, it is necessary to derive the terminal voltage of the multiplying electrode from a source having an internal resistance which is less than a critical maximum value. This value can be read off in said Fig. 1, in the usual way, from the reciprocal value of the slope of the straight line CDE, indicating the critical resistance. The working point C can be adjusted either by using a source of voltage OA, the internal resistance of which is practically zero, or else by using a smaller voltage OB and a series resistance, the value of which is indicated by the straight line BC. The limit for stable working is the use of a source of voltage OD in conjunction with a resistance graphically depicted by the straight line CDE.

The minimum no-load voltage OD to be fur-

nished by the voltage source coincides in practice with the voltage OF at which the sign of the multiplying electrode current reverses. However the magnitude of this voltage OF is indicative of the secondary emission properties of the multiplying electrode, as it indicates at what velocity of the electrons the number of the secondary electrons will be equal to the number of the primary electrons. When supplying the multiplying electrode from a source of voltage through a series resistance, care must be taken that the minimum no-load voltage exceeds the value OF. On the other hand the no-load voltage of the source must not exceed the working voltage OA. As the working voltage of the multiplying electrode must be less than the anode voltage, it is an obvious expedient to obtain the voltage of the multiplying electrode from the higher anode voltage by means of a voltage divider circuit. The dimensioning of the voltage divider is determined in accordance with the foregoing considerations, by the fact that under no load (when the electrode is carrying no current) the voltage of the multiplying electrode exceeds the minimum voltage aforesaid. In the circuits according to this invention this lower limit of no-load voltage is fixed at 50 volts, as the characteristic range of potentials for surfaces capable of secondary emission lies between 15 and 50 volts.

30 A feed circuit with a voltage divider is shown in Fig. 2. In this figure, as well as in the succeeding figures, 1 is the electron multiplier tube, 2 its incandescent cathode, 3 its control grid, 4 its screen grid, 5 its working anode and 6 its multiplying electrode. Also, 7 is the grid leak resistance, 8 is the coupling condenser in the input circuit, 9 is the cathode resistance, 10 and 13 are decoupling condensers, and 11 and 12 are resistances which constitute the voltage divider for the screen grid voltage. Further, 14 is the anode resistance and 15 is the coupling condenser in the output circuit. The voltage divider for feeding the multiplying electrode is constituted by the resistances 17 and 16, the resistance 17 being provided with an alternating current shunt through the condenser 18. The input is denoted by I, I' and the output by O, O'. The heating of the incandescent cathode need not be described but an indirectly heated cathode is shown. The source of voltage is connected to the terminals -V, +V.

35 A suitable dimensioning of the voltage divider in accordance with this invention will now be described. If, for example, the voltage of the source of energy amounts to 400 volts, the voltage on the

multiplying electrode 250 volts and the current taken by said multiplying electrode 6 mA., and if the no-load voltage on this electrode is to be 80 volts, the total resistance of the potentiometer or voltage divider must be 177,000 ohms, the component resistances 17 and 16 having the values 35,400 ohms and 141,600 ohms, respectively and the consumption will be 0.4 watt. If the working of the tube is to be made less dependent upon the current taken by the multiplying electrode, the resistances must be smaller and the no-load voltage higher, in which case the consumption of energy will be greater. As a second example, assuming that the operating voltages are the same and that the multiplying electrode takes the same working current, if a no-load voltage of 170 volts is chosen and if the values of the resistances 17 and 16 are 23,000 ohms and 30,000 ohms respectively, the voltage divider will consume 2 watts.

The direct current of the multiplying electrode or of the several multiplying electrodes in a circuit containing a plurality of multiplier tubes, can be used to supply anode direct current for other (ordinary) electron tubes having a working anode voltage which coincides very nearly with the working voltage on the said multiplying electrode or electrodes. The multiplying electrodes may work in parallel with a voltage source such as a mains rectifier to supply direct current energy for the same consumers.

Fig. 3 shows an example of a circuit comprising three electron multiplier tubes 1, 1', 1'' and an ordinary amplifying tube 20, employed as an output tube. In addition to the circuit elements, which are shown with the same reference symbols as in Fig. 2, condensers 18, 18' and 18'' play the same role as 18 in Fig. 2, while 19, 19' and 19'' severally denote chokes for decoupling the multiplying electrodes. In this figure, additionally, 21 denotes the incandescent cathode, 22 the control grid, 23 the screen grid, 24 the suppressor grid and 25 the anode of the output tube 20, for which 26 is the grid leak resistance. Further, 27 is the cathode resistance, 28 and 30 decoupling condensers and 31 is the anode resistance. The multiplying electrodes of the electron multiplier tubes are connected to the point of supply Sp for the anode of the ordinary electron tube. This point of supply Sp is connected through the resistance 29 to the + pole of the source of voltage. If the operating data for the multiplier tubes is assumed to be the same as in the foregoing example (multiplying electrode voltage 250 volts, anode voltage 400 volts, multiplying electrode current 6 mA.) we get back from the three tubes $3 \times 6 = 18$ mA., which, for a voltage of 250, means an economy of 4.5 watts in power consumption. The additional consumption in the resistance 29, which constitutes the second part of the voltage divider, amounts to $150 \text{ volts} \times 22 \text{ mA.} = 3.3$ watts if 40 mA. anode current is assumed for the output tube. In the alternative arrangement in which the multiplying electrodes are supplied by separate voltage dividers, there must be added to the calculated potentiometer consumption of the first example ($3 \times 0.4 = 1.2$ watts) the consumption in the series resistance 29 for the output tube ($40 \text{ mA.} \times 150 \text{ volts} = 6$ watts).

The economy of the circuit according to Fig. 3 can be reckoned in the following way: the total consumption, apart from the consumption of the output anodes amounts to $400 \text{ volts} \times 22 \text{ mA.} = 8.8$ watts. On the other hand, when separate voltage

dividers are used, it is necessary to add on to the voltage divider consumption of 1.2 watts the consumption due to the anode current of the output tube, which amounts to $400 \text{ volts} \times 40 \text{ mA.} = 16$ watts. The increase is nearly 50%. In addition to the saving in current, however, the circuit shown in Fig. 3 ensures greater stability because, owing to the low voltage divider resistances, the working currents are less dependent on the characteristics of the tube.

In the circuit arrangement shown in Fig. 4, a separate source of voltage $-V'$ $+V'$ is provided for the supply to the anodes of the multiplier tubes, so that a series resistance becomes superfluous. If the current consumption of the ordinary electron tube or tubes is too small, it may happen that the demand for an adequately high no-load voltage when the multipliers are carrying no current is not fulfilled. In this case it is advisable to connect a loading resistance 32 in shunt with the consumer tube or tubes so as to ensure the stability of the supply to the multipliers. Both the series resistance 29 in the example shown in Fig. 3 and the loading resistance 32 in the example shown in Fig. 4 can be replaced by the field coil of a loud speaker. It is also possible to utilise the consumer resistance in connection with 32 of Fig. 4 as a voltage divider for supplying any electrodes of the tubes of the amplifying circuit which require a lower supply voltage.

The circuit conditions thus far described serve to economise in the current consumption of multiplier tubes while ensuring their stable working insofar as the desired supply voltages for the multiplying electrodes adjust themselves to working conditions. For the stable working of amplifier tubes it is, however, also desirable to ensure, by suitable circuit conditions, that unavoidable variations in the characteristic curves of the tubes during working or due to differences in individual tubes is adequately compensated, so that such defects are minimised as far as possible.

As is well known, the ordinary commercial amplifier tubes show deviation in the sense that the anode-current grid-voltage curves tend to parallel displacement around a certain grid voltage value. In the usual circuits, the shifting or displacement of the working point caused in this way is partially compensated by not using a fixed grid bias but making the grid biasing voltage proportional to the cathode current. This condition is easily attained by using a cathode resistance, the voltage drop in which provides the grid bias. In multiplier tubes however, the anode current is derived only in part from the primary cathode current and is due mainly to the current of the multiplying electrode. Thus, if only the ordinary cathode resistance were used, fluctuations of the primary current would be compensated, but not those of the secondary current. It would, however, be desirable, when the multiplying electrode current decreases (owing, for instance to a reduction in the secondary emission) for the anode current to be increased automatically, as, for example, by a reduction of the bias on the control grid. These conditions can be obtained, according to the present invention, by a circuit arrangement such as that which is shown diagrammatically in Fig. 5.

The characteristic feature of the circuit shown in said Fig. 5 is that the multiplying electrode is connected not only to a positive feed point,

through resistance 16, but also to the cathode, through a resistance 33. The cathode resistance 9 is traversed, both by the cathode current and by that part of the current of the multiplying electrode which flows through the resistance 33. If then the multiplying electrode current diminishes while the tube is in use, the voltage on this electrode and, therefore, the current passing through the resistance 33, will be less and so also will be the current passing through the cathode resistance 9. In consequence of this the voltage drop across the cathode resistance is reduced, this voltage drop determining, wholly or in part, the value of the grid bias. Reducing the grid bias increases the primary electron current, so that both the multiplying electrode current and the anode current of the tube are increased.

It is possible to render such a compensation for avoiding unwanted variations of direct current still more efficient by making the cathode resistance as large as possible compared with the reciprocal value of the slope of the multiplier tube. In order to adjust the grid bias correctly when the value of the cathode resistance is high, it is necessary for the direct current grid connection to be taken to a point the potential of which is positive in relation to the negative terminal of the source of voltage. In the example shown in Fig. 5 this is done by connecting the grid not only (as usual) through a resistance 7 to the negative terminal $-V$ of the source of voltage, but also through a higher resistance 34 to the positive terminal $+V$ of the same source $-V +V$. The voltage divider formed by the resistances 7 and 34 determines the voltage of the control grid in relation to the negative terminal $-V$ of the source of voltage.

Amplifier circuits according to this invention can with advantage be incorporated in television receiving apparatus and in such cases the source of voltage for the anodes of the electron multipliers can be used simultaneously for supplying the deflectors or sweep voltage devices for line and frame scanning in the picture tube.

What we claim is:

1. An amplifier circuit including at least one electron multiplier tube therein having an emissive source of primary electrons, a control grid, a screen grid, a multiplying electrode, and an output anode, together with means for heating said emissive source, said amplifier circuit further including one or more amplifier tubes following said multiplier tube, characterized by the fact that said circuit is provided with means constituting a voltage divider for the D. C. current feed to the multiplying electrode of said tube and with means constituting a voltage divider for the screen grid voltage thereof, the first-named divider being so proportioned or dimensioned and operable that for zero current in said multiplying electrode the accelerating voltage on the same has a value which exceeds fifty volts with reference to the emissive source, but is less than the working voltage for said multiplying electrode, said multiplying electrode being connected with the anodes of said amplifier tubes in such a way that the current yielded by the multiplying electrode is used in part or wholly for the supply of anode direct current to other amplifier tubes placed in the circuit.

2. An amplifier circuit according to claim 1, including also a source of direct current connected in parallel with a multiplying electrode of a multiplier tube so that the multiplying elec-

trode and the source of direct current act as parallel sources of energy for at least one conventional amplifier tube in the amplifier circuit.

3. An amplifier circuit including at least one electron multiplier tube therein having an emissive source of primary electrons, a control grid, a screen grid, a multiplying electrode, and an output anode, together with means for heating said emissive source, characterized by the fact that said circuit is provided with means constituting a voltage divider for the feed to the multiplying electrode of said tube and with means constituting a voltage divider for the screen grid voltage thereof, the first-named divider being so proportioned or dimensioned and operable that for zero current in said multiplying electrode the accelerating voltage on the same has a value which exceeds fifty volts with reference to the emissive source, but is less than the working voltage for said multiplying electrode, said circuit including also at least one other amplifying tube connected with said multiplier tube, said other amplifying tube having a separate voltage source for its anode and said multiplying electrode being connected with the anode of said amplifier tube in such a way that the current yielded by the multiplying electrode is used in part or wholly for the supply of anode direct current to same.

4. An amplifier circuit including therein at least one electron multiplier tube having each at least one multiplying electrode, an emissive source of primary electrons together with means for heating said source, a control grid, an accelerating grid and an output anode, said amplifier circuit further including at least one conventional amplifier, and said multiplying electrode being connected with the anode of said conventional amplifier, further characterized by the fact that said circuit is provided with means constituting a voltage divider for the feed of potential to said multiplying electrode of the said tube, the said voltage divider being so proportioned or dimensioned and arranged that for zero current in said multiplying electrode of said tube the accelerating voltage on the same has a value which exceeds fifty volts with reference to the emissive source, but is less than the working voltage for said multiplying electrode, the current yielded by said multiplying electrode being used in part or wholly for the supply of anode direct current to said connected amplifier.

5. An amplifier circuit including therein at least one electron multiplier tube having at least one multiplying electrode connected with the anode of at least one conventional amplifier included also therein, a common source of anode direct current for said multiplier tube and said amplifier, said circuit being characterized by the fact that it is provided with means constituting a voltage divider for the feed of potential to said multiplying electrode of the said multiplier tube and with means constituting a voltage divider also for the screen grid voltage of said tube, the first-named voltage divider being so proportioned or dimensioned and operably arranged that for zero current in said multiplying electrode of said tube the accelerating voltage on the same has a value which exceeds fifty volts with reference to the emissive source, but is less than the working voltage for said multiplying electrode, said multiplying electrode being connected with the anode of said amplifier tube in such a way that the current yielded by said multiplying electrode is used in part or

wholly for the supply of anode direct current to said connected amplifier.

6. An amplifier circuit including therein at least one electron multiplier tube having at least one multiplying electrode connected with the anode of at least one conventional amplifier included also therein, a separate source of anode direct current for said amplifier, said circuit being characterized by the fact that it is provided with means constituting a voltage divider for the feed of potential to said multiplying electrode of the said multiplier tube and with means constituting a voltage divider also for the screen grid voltage of said tube, the first-named voltage divider being so proportioned or dimensioned and operably arranged that for zero current in said multiplying electrode of said tube the accelerating voltage on the same has a value which exceeds fifty volts with reference to the emissive source, but is less than the working voltage for said multiplying electrode, said multiplying electrode being connected with the anode of said amplifier tube in such a way that the current yielded by the multiplying electrode is used in part or wholly for the supply of anode direct current to said connected amplifier.

7. An amplifier circuit having therein at least one electron multiplier tube and at least one other amplifier tube, characterized by a provision of means in said circuit for effecting the feed to the multiplying electrodes of said tube in such a way that for zero current in the said multiplying electrodes the accelerating voltage on the latter has a value which exceeds fifty volts with reference to the primary cathode in the case of a single or the first multiplying electrode and with reference to the preceding multiplying electrode in the case of successive multiplying electrodes, but is less than the working voltage for said multiplying electrodes, said multiplying electrodes being connected to the anode of said amplifier tube in such a way that the direct current yielded by the multiplying electrodes is used wholly or in part for the supply of anode direct current to other said amplifying tube.

8. An amplifier circuit according to claim 1, including also an auxiliary resistance connected in parallel with the anode circuit of a conventional amplifier tube receiving anode direct current from a multiplying electrode of a multiplier tube, whereby to ensure stable operating conditions in which the total current consumption in all operating circumstances adequately ex-

ceeds the current delivered by the multiplying electrode.

9. An amplifier circuit including a plurality of electron multiplier tubes each having an emissive source of primary electrons, a control grid, an accelerating grid, a multiplying electrode, and an output anode, together with means for heating said emissive source, said amplifier circuit further including an ordinary amplifier tube employed as an output tube, the energy supplying circuits of said multiplier tubes being connected in parallel with the anode feed circuit of said ordinary amplifying tube, and said amplifier circuit being provided with a voltage divider for the feed of potential to the multiplying electrodes of the several multiplier tubes, the said divider being so dimensioned and operatively arranged that for zero current in said multiplying electrodes the accelerating voltage on the same has a value which exceeds fifty volts with reference to their emissive sources, but is less than the working voltage for said multiplying electrodes, the parallel connection of the energy supplying circuits of said multiplier tubes with the anode feed circuit of said ordinary amplifying tube constituting one part of said voltage divider and the other part thereof being constituted by an ohmic resistance such for example as the field coil of a loud speaker, the positive terminal of the D. C. supply being connected through the ohmic resistance to the common supply point of the tubes.

10. An amplifier circuit according to claim 9, wherein an additional source of voltage is provided for the anodes of the multiplier tubes.

11. An amplifier circuit according to claim 1, further characterized by a resistance between the multiplying electrode and the cathode of the same multiplier tube, said resistance being proportioned or dimensioned so that a portion of the current supplied by said multiplying electrode is passed through the cathode resistance of said tube.

12. An amplifier circuit according to claim 1, wherein a grid biasing resistance is included in the anode circuit of the multiplier tube and the multiplying electrode is connected to the emissive source of primary electrons through said resistance of such a size that the values of the grid bias are automatically regulated according to the variations of the multiplying electrode current so as to attain stable conditions.
